DESIGN FOR A POCKET WATCH HOLDER

Martin Pientkewic, Vulcan, Mich.

Application May 20, 1942, Serial No. 106,959

Term of patent 3½ years

To all whom it may concern:

Be it known that I, Martin Pientkewic, a citizen of the United States and resident of Vulcan, in the county of Dickinson, in the State of Michigan, have invented a new, original, and ornamental Design for a Pocket Watch Holder, of which the following is a specification, reference being had to the accompanying drawing, forming a part thereof.

Figure 1 is a front elevational view of a pocket watch holder, Figure 2 is a side elevational view of the same, Figure 3 is a top plan view of the same, and Figure 4 is a rear elevational view of the same, showing my design.

I claim:

The ornamental design for a pocket watch holder, as shown.

MARTIN PIENTKEWIC.
